UNITED STATES PATENT OFFICE

140,281

DESIGN FOR A COMBINED DESK AND SEAT

Albert K. Weller and William H. Dozier, Jr.,
Portland, Oreg.

Application April 15, 1944, Serial No. 113,264

Term of patent 14 years

(Cl. D33—7)

To all whom it may concern:

Be it known that we, Albert K. Weller and William H. Dozier, Jr., citizens of the United States, residing at Portland, in the county of Multnomah and State of Oregon, have invented a new, original, and ornamental Design for a Combined Desk and Seat, of which the following is a specification, reference being had

to the accompanying drawing, forming a part thereof, in which the figure is a perspective view of a combined desk and seat, showing our design.

We claim:

The ornamental design of a combined desk and seat, as shown.

ALBERT K. WELLER.

WILLIAM H. DOZIER, JR.
